UNITED STATES PATENT OFFICE.

ROBERT W. COOK, OF ROCHESTER, NEW YORK, ASSIGNOR TO EASTMAN KODAK COMPANY, OF ROCHESTER, NEW YORK, A CORPORATION OF NEW YORK.

WASHING APPARATUS FOR FIBROUS MATERIALS.

Application filed October 17, 1921. Serial No. 508,376.

To all whom it may concern:

Be it known that I, ROBERT W. COOK, a citizen of the United States of America, residing at Rochester, in the county of Monroe and State of New York, have invented certain new and useful Improvements in Washing Apparatus for Fibrous Materials, of which the following is a full, clear, and exact specification.

- 10 This application relates to an improved washing apparatus for fibrous material. The objects of this invention are to provide a device of this type which is simple in operation and construction, in which material 15 of the nature described may be quickly and thoroughly washed, and from which such material may be removed by a single operation, the entire contents being discharged at one time without leaving small portions of 20 the material that must be carefully picked out. These objects are attained by the use of a container with foraminous sides and bottom through which the material will not pass and which slope to a large outlet, 25 which when opened is entirely unobstructed, water reaching the material only through these walls. The force of the water coming through the walls will carry the material with it through the outlet.
- 30 The above and other ends are attained by the structure, one embodiment of which is fully described hereinafter and the novel features of which are recited in the appended claims.

35 Reference will now be made to the accompanying drawing in which:

Fig. 1 is a perspective view of my improved tank;

Fig. 2 is a front elevation thereof, and

40 Fig. 3 is a perspective view of the foraminous container alone.

The apparatus consists of a tank 1, having side walls 2, 3, 4, and 5, and a bottom wall 6. Within the tank is a container 40 45 comprising three walls 7, 8, and 9, the upper edges of which are attached to the walls 3, 4, and 5 respectively. These three walls incline to form an inverted pyramid. The front edges 10 and 11 of the walls 7 and 9 50 respectively form tight joints with the inside of the front wall 2 of the outer tank, meeting at the apex or point 12 at the bottom of the tank and the front thereof. The meeting edge 13 between walls 7 and 8 inclines to the same point as does the meeting

edge 14 of the walls 8 and 9. These walls are formed of foraminous material and preferably are of wood with a large number of small holes bored therethrough. In the drawing, for the sake of clearness, these 60 holes appear rather large and further spaced apart than in practice, but I find it preferable to make a large number of very small holes. A suitable washing liquid such as water is admitted through the pipe 15 by 65 means of a stopcock 16 to the interior of the tank at a point in the lower portion thereof outside of the container 40.

In the front wall 2 is a large aperture 18 opening into the inner container 40, the 70 portions of the opening below the edges 10 and 11 being closed by suitable stop-blocks 19 so that water or other material will escape only from the container 40. A bar 20 is hinged at 21 to the front 2 of the tank 75 and this bar carries a hand screw 22, which in turn carries a closure 23 for the opening 18. The other end of the bar 20 is supported in lowered position by a bracket 24. When the bar is lowered and the screw 80 turned the closure 23 is forced tightly up against the borders 25 of the opening 18, forming a water tight closure, suitable packing, of course, being carried by the member 23. Overflow pipes 26 are provided at 85 the top of the tank, these opening into the container 40. A further outlet pipe 27 provided with a stopcock 28 is also provided, this opening from the bottom of the outer tank.

In use the fibrous material such as raw cotton, wood pulp, nitrated cotton and the like is placed in the container and water admitted from pipe 15. As the tank fills the water will enter the container 40 through 90 the foraminous walls and overflow through the pipes 26, which are provided with suitable strainers 26' to prevent fibrous material passing therethrough. If desired, the water may be withdrawn entirely from time to 100 time from the tank and container by means of the stopcock 28. When the charge of fibrous material is to be removed from the tank, the stopcock 16 is left open so that there will be a pressure of water upwardly 105 through the foraminous walls of the container. The screw 22 is loosened and bar 20 thrown to the position shown in Fig. 2. The large outlet opening is then entirely unobstructed and the contents of the container 110

- are discharged in a mass. Because of the inward rush of the water into the container through all of the apertures of its wall, the fibrous material does not become entangled 5 in the openings in these walls, but the water forces them with it out of the main discharge opening. It is obvious that the water cannot reach this discharge opening except through the foraminous walls so that there 10 is a considerable volume of water operative to carry the charge of the apparatus out with it. It is obvious, therefore, that the washing tank can be emptied with the greatest ease and that there will not be, as is often 15 the case with other tanks designed for similar purposes, the necessity for picking out remaining fragments and fibers that have attached themselves to the walls of the apparatus.
- 20 It is apparent that changes may be made in the structure and I contemplate all such improvements and equivalents as fall within the scope of my invention as defined in the accompanying claims.
- 25 Having thus described my invention, what I claim as new and desire to secure by Letters Patent is:
1. Apparatus of the type described comprising a tank with side and bottom walls, a 30 container in the tank having at its bottom a large outlet through a wall of the tank, and having a foraminous wall sloping to said outlet, a closure for the outlet, and means for admitting liquid to the tank outside of 35 and beneath the top of the container.

2. Apparatus of the type described comprising a tank, a container within the tank having a foraminous wall and having a large outlet through the tank, a closure for said outlet so movable as to leave the outlet entirely unimpeded, the wall sloping to the outlet, and means for admitting liquid to the tank outside of and below the top of the container. 40

3. Apparatus of the type described comprising a tank, a container within the tank having foraminous walls and having a large outlet through the tank, means for admitting liquid to the tank outside of said container and below the top thereof, whereby liquid admitted through said means may reach said outlet only through the foraminous walls. 45

4. Apparatus of the type described comprising a tank with side and bottom walls, a container within the tank having foraminous walls joined to the side walls of the tank and having a large outlet through a wall of the tank, the walls of the container sloping to said outlet, means for admitting liquid to the tank outside of said container and below the top thereof, whereby liquid admitted through said means may reach said outlet only through the foraminous walls, and a closure for said outlet adapted 60 to be moved so as to leave the closure entirely unimpeded. 65

Signed at Rochester, New York, this 10th day of October 1921.

ROBERT W. COOK.
